UNITED STATES PATENT OFFICE.

HARVEY KEITH MACKENZIE, OF KIMBERLEY, BRITISH COLUMBIA, CANADA.

DRILL-EXTRACTOR.

1,202,551.

Specification of Letters Patent. Patented Oct. 24, 1916.

Application filed September 16, 1914. Serial No. 862,083.

To all whom it may concern:

Be it known that I, HARVEY K. MACKENZIE, a subject of England, and a resident of Kimberley, in the Province of British Columbia and Dominion of Canada, have invented a new and useful Improvement in Drill-Extractors, of which the following is a specification.

My invention is an improvement in drill extractors, and has for its object to provide a device of the character specified, adapted for use with power operated drills for extracting drill steels when jammed in the drill hole, and wherein the power of the drill is utilized for extracting the steel.

In the drawings:—Figure 1 is a side view of the improvement in use, Fig. 2 is a side view of a portion of the attachment with a part in section, Fig. 3 is a view of the said portion at right angles to Fig. 2, Fig. 4 is a perspective view of the link, and Fig. 5 is a similar view of the key.

The present embodiment of the invention is shown in connection with a power operated drill 1, of ordinary construction, having connected therewith the pressure supply pipe 2, which is controlled by a valve 3, arranged between the said pipe and the drill. The steel 4 is shown jammed in the drill hole, the said steel being cruciform in cross section.

A bar 5 having a portion of the length thereof cruciform in cross section as indicated at 6, is provided, the said bar having at the opposite end from the cruciform portion a transverse pin 7, whose ends extend beyond the opposite faces of the bar. Between the pin and the cruciform portion the bar is provided with a pair of shoulders 8 and 9, the said shoulders facing in opposite directions.

The shoulder 8 is adjacent to the pin 7 and at one edge of the bar while the shoulder 9 is at the opposite edge. The two shoulders are beveled in the same direction, and their faces are parallel. The bar is adapted to be inserted in the chuck of the drill, the cruciform portion being engaged with the chuck, the said portion being of approximately the same shape and size as the drill stem.

A link is used in connection with the bar, the link being shown in Fig. 4. This link 10 is provided at one end with a slot 11, for receiving the upper end of the bar 5, the slot however, being of greater length

than the width of the plain portion of the bar. The slot is of approximately the same width as the thickness of the bar, so that it may be easily inserted over the plain end 60 of the bar when the bar is held in the chuck.

At the opposite end the link is provided with an eye or loop 12, and one end of a cable 13 is engaged with the eye, the end of the cable being passed through the eye and 65 being then secured to the body of the cable, as indicated at 14. A key 15 is used in connection with the drill steel, the key having at one end a head 16, provided with a transverse opening 17 of cruciform cross section 70 and shaped to fit the drill steel.

Between the head and the body of the key a perforated lug 18 is provided on the upper face of the key. This lug is adapted for engagement by the opposite end of the cable 75 13 from the link 10, as clearly shown in Fig. 1. The end of the cable is passed through the perforated lug and a clamp 19 is provided for clamping the said end to the body of the cable. 80

The operation of the improvement is as follows:—When a drill steel becomes jammed in the drill hole, the bar 5 is inserted in the chuck of the drill, the cruciform portion being engaged with the chuck. The 85 drill is then reversed, and the rod or peg 20 of the feed cylinder is inserted in an opening in the ground close to the drill steel. The key 15 is then engaged with the steel, the steel being passed through the cruciform 90 opening of the head. The link 10 is normally connected with the bar 5 in the manner shown in Figs. 1 and 2, the pin 7 preventing disengagement of the link. The shoulders 8 and 9 are beveled in such manner that when the link is in place it will rest as shown in Fig. 2, engaging both shoulders throughout their extent, the under face of the link at one end of the opening 11 engaging one shoulder and the upper 95 face of the link at the opposite end of the opening engaging the other. The cable 13 which is normally connected with the eye of the link, is now connected with the key, the end being passed through the perforation and being then clamped to the body of 100 the cable. With the parts in this position, the motive fluid is admitted to the drill. As the hammer of the drill reciprocates, the bar 5 will be struck and will make traction on 110 the cable 13, thus jarring the drill steel through the key 15. At the same time the

feed mechanism will make steady continuous traction on the cable 13 in the direction of its length, and it will be evident that but little time will be required to loosen the drill 5 wherein steady traction and intermediate jarring are used together. The key may also be utilized for rotating the drill if desired.

It will be understood that the improvement may also be used to remove a bit with a steady pull, and without operating the hammer. As for instance, when the bit sticks in a muddy hole, the link 10 is permitted to slip down over the shoulder 9 until it rests upon the shoulder formed by the cruciform portion of the bar 5. This permits the bar 5 being inserted but a short distance into the chuck of the drill and with the bar in this position the hammer of the 20 drill will not operate, that is, it will not strike the bar 5. The feeding mechanism of the drill is now started and the bar 5 will be moved away from the key steadily without any jerking or jarring. Hence the 25 pull is a steady pull without jarring.

I claim:—

1. A drill extractor to be used in connection with a power drill, and comprising a key having an opening in one end shaped 30 to fit and receive the drill stem, a bar having one end adapted to fit within the chuck of the drill, said bar having pairs of oppositely arranged stops at the opposite end and spaced apart from each other longitudinally 35 of the bar, a link having an opening at one end for receiving the said end of the bar and adapted to engage either pair of stops to limit the inward movement of the link, and a flexible connection between the other 40 end of the link and the key intermediate its ends and of sufficient length to permit the reversed drill to be placed with its feed end engaging the surface from which the drill is to be extracted with the bar in place in 45 the chuck.

2. A drill extractor for use in connection with a power drill, and comprising a key having an opening in one end for receiving

the drill stem, a bar having one end shaped to fit within the chuck of the drill, a link 50 having an opening for receiving the other end of the bar when the bar is in place in the drill, a flexible connection between the key and the link, and a plurality of stops in connection with the bar for engagement by 55 the link to limit the movement thereof toward the drill chuck, said stops being spaced apart longitudinally of the bar.

3. In combination with a power drill having feed mechanism, of a drill extractor 60 comprising a key having an opening for receiving the stem at one end of the key, a bar adapted to fit within the chuck of the drill at one end and to extend beyond the chuck at the other end, a link having an 65 opening for engaging the said end of the bar, said bar having a plurality of stops for engagement by the link to limit the movement thereof toward the chuck, and the stops being spaced apart longitudinally of 70 the bar, and a flexible connection between the link and the key intermediate the ends of the key and of sufficient length to permit the feed rod of the drill to be engaged with the surface in which the drill stem is held 75 with the bar in place in the chuck.

4. In combination with a power drill having feed mechanism, of a drill extractor comprising a key having an opening for receiving the stem at one end of the key, a 80 bar adapted to fit within the chuck of the drill at one end and to extend beyond the chuck at the other end, a link having an opening for engaging the said end of the bar, said bar having a stop for engagement 85 by the link to limit the movement thereof toward the chuck, and a connection between the link and the key intermediate the ends of the key and of sufficient length to permit the drill to be reversed with the feed rod 90 contacting with the surface engaged by the drill stem with the bar in place in the chuck.

HARVEY KEITH MACKENZIE.
